PRESSURE ACTUATED PUNCHING
MECHANISM

Dudley W. Hart, Phillipsburg, N. J., assignor to
Ingersoll-Rand Company, Jersey City, N. J., a
corporation of New Jersey

Application July 16, 1931. Serial No. 551,165

2 Claims. (Cl. 76—5)

This invention relates to punching mechanism, but more particularly to a punching mechanism adapted for pinning out the ends of hollow bores of working implements, such as drill steels and the like, and in which the bore or portions thereof have become deformed during prior forging operations.

One object of the invention is to effect such pinning out or punching of drill steels through the application of indirect blows delivered to the punching mechanism and transmitted thereby to the punch pin.

Another object is to effect the withdrawal of the punch pin from the drill steel by indirect blows of the hammer piston applied to the punching mechanism, and another object is to provide a punching mechanism with arresting means adapted to render alternate blows of the hammer piston ineffective to move the casing with respect to the article being punched.

Other objects will be in part obvious and in part pointed out hereinafter.

In the drawing accompanying this specification and in which similar reference characters refer to similar parts,

Figure 1 is a longitudinal sectional elevation of a punching mechanism constructed in accordance with the practice of the invention, and

Figure 2 is a transverse view taken through Figure 1 on the line 2—2 looking in the direction indicated by the arrows.

Referring more particularly to the drawing, the punching mechanism constructed in accordance with the practice of the invention and designated generally by A is mounted upon a support B comprising a bracket C which may be suitably secured to a clamping device D of a well known type. The clamping device D may, as is customary, consist of a base member E and a clamping die F movable relatively to the base member E and cooperating therewith to clamp the work, such as a drill steel G, securely in position.

On the outer or free end of the bracket C is a vertical extension H which supports one end of guide rods J whereon the punching mechanism A is slidably mounted. The opposite ends of the guide rods J may be conveniently threaded into the base member E and said guide rods lie in the same transverse plane and are parallel with respect to each other.

The punching mechanism A comprises a cylinder K bored to form a piston chamber L which consists in this instance of an enlarged portion O and a rearward reduced portion P to accom-

modate a reciprocating hammer piston Q. The hammer piston Q may be of a well known type having a head R slidably in the enlarged portion O of the piston chamber, and a rearward extension S which is guided by the reduced portion P of the piston chamber.

In mechanisms employing pistons of the type described the extension S may serve as a means for controlling the distribution of pressure fluid to the various portions of the piston chamber L for actuating the piston Q. The extension S is accordingly provided with an annular groove T near the point of union of said extension and the head R to establish communication between the rear end of the enlarged portion O and a supply passage U leading from the rear end of the reduced portion P of the piston chamber to a point in said reduced portion slightly rearwardly of the rear end of the enlarged portion O of the piston chamber.

The neck or groove T is of such extent that when the piston Q approaches its rearmost limiting position in the piston chamber the groove T will establish communication between the passage U and the rear end of the enlarged portion O of the piston chamber.

The pressure fluid thus distributed may be introduced directly into the rear end of the reduced portion P which will therefore act as a constant pressure chamber and in consequence of which the rear end V of the extension S will be constantly exposed to pressure fluid tending to actuate the piston Q forwardly.

The admission of pressure fluid to the front end of the piston chamber L is likewise controlled by the extension S. Such pressure fluid is conveyed to this end of the piston chamber by an inlet passage W having its inlet port X located intermediate the ends of the reduced portion P of the piston chamber. Thus arranged the inert port X will be uncovered by the rear end of the extension S as the piston approaches its forward limiting position to admit pressure fluid into the front end of the enlarged portion O of the piston chamber.

The outlet port Y of the inlet passage W preferably opens into the enlarged portion O of the piston chamber at a point located somewhat rearwardly of the extreme front end of said enlarged portion O so that, during the operation of the punching mechanism, the piston will at all times be prevented from striking a direct blow against a front head Z which forms a closure for the front end of the piston chamber L. In other words, the supply and inlet passages

and the elements whereby they are controlled are so arranged that during both the forward and rearward stroke of the piston the end of the piston chamber toward which the piston Q 5 is moving will be charged with pressure fluid to assure prompt reversal of the piston before said piston may come into contact with the closures for the ends of the piston chamber, as for instance, the front head Z and a back head b which 10 seals the rear end of the reduced portion P of the piston chamber.

In accordance with a well understood practice, in apparatus employing pistons of the character described, pressure fluid utilized for actuating the piston is exhausted only from the enlarged portion O of the piston chamber. The cylinder K is accordingly provided with an exhaust port c located intermediate the ends of the enlarged portion O and controlled by the head R of the 20 piston Q.

Preferably the cylinder K is provided with a pair of lugs d located near the extremities of said cylinder and having bores e therein to receive the guide rods J whereby the punching mechanism A is supported with respect to the 25 drill steel G.

The front head Z and the back head b may be secured fixedly to the cylinder K in any suitable manner, as for instance by side rods f arranged 30 on opposite sides of the cylinder K and having nuts g threaded on one end thereof to clamp the heads securely against the ends of the cylinder K.

In addition to serving as a closure for the front end of the piston chamber L the front head Z 35 also acts as a holder for the working implement, such as a punch pin h. To this end the front head may be provided with a forwardly directed extension j having a bore k to receive a shank o of the punch pin h. The punch pin h may be 40 secured in the extension j in any suitable manner, as for instance by a pin p which extends through registering apertures in the shank o and the extension j to lock these elements securely together. A retaining element, such as a spring 45 q, may be disposed about the extension j to overlie the ends of the pin p and thus prevent end-wise movement of the said pin.

As will be observed the punching mechanism A is so located with respect to the clamping elements E and F that the punch pin h will lie in the axial plane of the drill steel G and therefore in the plane of a passage r within the drill steel, and which passage or portions thereof the punch pin h is adapted to open.

55 The operation of the apparatus so far described is as follows: With the rear end of the reduced portion P of the piston chamber open to pressure fluid supply, pressure fluid flowing into said reduced portion will act against the rear end V of the extension S to drive the piston Q forwardly. The pressure acting against this end of the piston will be assisted by pressure fluid previously admitted from the supply passage U through the annular groove T into the rear end 60 of the enlarged portion O of the piston chamber and acting against the rear end of the head R. As the piston Q moves forwardly the head R will uncover the exhaust port c and pressure fluid will then be exhausted from the rear end of the enlarged portion O to the atmosphere.

70 With the piston in this position the rear end of the extension S will uncover the inlet passage W. Pressure fluid will then be admitted into the front end of the enlarged portion O of the piston chamber to reverse the piston. Upon such re-

versal of the piston a sharp jar or indirect blow will be transmitted to the front head Z which will carry the entire punching mechanism in the direction of the drill steel G and will therefore drive the punch pin h into the passage r of the drill steel.

80 Admission of pressure fluid into the front end of the piston chamber L may continue throughout a brief portion of the rearward travel of the piston Q after which communication between the inlet passage W and the reduced portion P of the piston chamber will be cut off by the extension S of the piston, so that only the extreme ends of the piston chamber will be exposed to pressure fluid. Inasmuch that the front end of the head R of the piston Q is of larger area than the end V of the extension S the pressure in the front end of the enlarged portion O will predominate over that acting against the end V, the piston Q will be carried rearwardly

85 until it uncovers the exhaust port c, whereupon the pressure fluid will be exhausted from the front end of the enlarged portion O to the atmosphere. When the piston reaches this position the groove T in the extension S will again 90 establish communication between the supply passage U and the rear end of the enlarged portion O of the piston chamber to admit pressure fluid thereinto to assist in driving the piston forwardly.

95 Upon reversal of the piston at the rearmost limit of its travel a jar or indirect blow will of course also be imparted to the punching mechanism and which jar in the absence of suitable arresting devices would of course tend to again 100 withdraw the punch pin from the drill steel G. In order to prevent such withdrawal of the punch pin the punching mechanism is provided with suitable arresting means adapted to selectively render alternate jars of the hammer piston Q 105 ineffective to disturb or alter the position of the punching mechanism A with respect to the drill steel G.

110 The arresting means selected for illustrative purposes is like that disclosed in U. S. Patent No. 1,788,034 granted to William A. Smith, Sr., January 6, 1931 in which the arrangement, briefly described, consists of a bracket, herein designated by s, and shown as forming an integral part of the back head b.

115 The bracket s has pivotally mounted thereon a friction shoe t adapted to be pressed into engagement with the surface of a rod u by pressure actuated plungers v and w. The rod u is supported at one end by the vertical extension H 120 and at its other end by the base member E of the clamping device. The plungers v and w are reciprocable in cylinders x and y respectively forming part of the bracket s and to which cylinders the pressure fluid may be supplied by a 125 throttle valve z arranged in a casing 2 mounted in this instance upon the bracket C.

130 The pressure fluid for actuating the plungers v and w may be carried to their respective cylinders by suitable flexible conduits 3 and 4 for actuating the friction shoe t from one engaging position to another and for holding said friction shoe in such engaging positions.

135 For a full description of the arresting device access may be had to the aforesaid patent. It may, however, be herein briefly stated that whenever it is desired to drive the punch pin h into the drill steel G the throttle valve z may be rotated to a position for supplying pressure fluid to the cylinder x. Such pressure fluid acting 140

against the plunger *v* will swing the friction shoe *t* forwardly and thus maintain the rearward portion thereof firmly in engagement with the surface of the rod *u*.

5 With the friction shoe *t* thus disposed the punching mechanism *A* may only travel in a forwardly direction, that is, in a direction toward the drill steel *G* upon reversal of the piston *Q* in the front end of the piston chamber, but, upon 10 reversal of the piston in the rear end of the piston chamber the friction shoe will, by its frictional engagement with the rod *u*, prevent the punching mechanism from being shifted in a rearwardly direction. It will be apparent, therefore, that only the alternate blows of the piston *Q*, or, in other words, those jars resulting during 15 the act of reversal of the piston *Q* in the front end of the piston chamber will be effective to carry the punching mechanism *A* along the 20 support.

By maintaining the friction shoe *t* in the position described the punching mechanism will be advanced in the direction of the work and the punch pin *h* will therefore be rapidly driven into 25 the drill steel.

After the passage *r* in the drill steel *G* has been properly shaped or reformed the throttle valve *s* may be reversed to admit pressure fluid into the cylinder *y*. This pressure fluid acting against 30 the plunger *w* will rock the friction shoe rearwardly so that the front portion of said friction shoe will be in engagement with the rod *u*. Meanwhile the piston *Q* will, of course, continue 35 its reciprocations and upon each reversal of such piston in the rear end of the piston chamber the entire punching mechanism will be carried rearwardly along the support *B*.

Upon reversal of the piston in the front end of the piston chamber the friction shoe will, by its 40 frictional engagement with the rod *u*, prevent any movement of the punching mechanism in the direction of the drill steel *G*. The punch pin *h*

will therefore be speedily withdrawn from said drill steel and to a position for a subsequent pinning out operation.

Certain very desirable advantages flow from the present invention. Foremost of these is the complete absence of direct impact of the hammer piston against the elements associated therewith, as for instance, the parts comprising the casing of the punching mechanism, and only indirect blows or cushioned jars will be imparted to such mechanism for driving the punch pin *h* into and out of the work. This is an extremely desirable feature and one that enables the entire punching mechanism to render service for long periods of time without necessitating replacements due to wear or breakage as has been the case in apparatus of this type heretofore.

I claim:

1. A punching mechanism comprising a casing having a working implement fixedly secured thereto, a member isolated from the working implement and reciprocable in the casing to cause longitudinal vibration thereof, supporting means for the casing, and means associated with the casing and its supporting means selectively to 95 resist vibration in one direction and to yield to vibration in the other direction whereby the casing may be caused to travel along the supporting means to drive the working implement into and withdraw it from the work. 100

2. A punching mechanism comprising a casing, the punching implement fixedly secured thereto, an element in the casing isolated from the punching implement and adapted to be reciprocated by pressure fluid to cause vibration of 110 the casing, a support for the casing, and means associated with the casing and its support selectively to respond to vibratory impulses to cause forward and backward movement of the casing and the punching implement lengthwise of the 115 support. 120
